UNITED STATES PATENT OFFICE.

EDWARD D. WOODS, OF MANCHESTER, VERMONT.

DESIGN FOR A COMBINED CLEAVER AND KNIFE.

SPECIFICATION forming part of Design No. 27,034, dated May 11, 1897.

Application filed March 5, 1897. Serial No. 627,246. Term of patent 14 years.

To all whom it may concern:

Be it known that I, EDWARD D. WOODS, of Manchester, in the county of Bennington and State of Vermont, have invented a certain 5 new and original Design for a Combined Cleaver and Knife, of which the following is a description.

Reference is to be had to the accompanying drawings, forming a part of this specification, 10 of which drawings—

Figure 1 is a side view of a cleaver and knife, showing my design. Fig. 2 is a cross-sectional view taken on the line 2 2 of Fig. 1.

The leading feature of my design consists 15 in the shape or configuration of the cleaver or knife blade as herein shown, the sides of the blade being inclined from a longitudinally central or nearly central line comparatively abruptly to one edge and from 20 the same longitudinal line appreciably less abruptly to the opposite edge, the outline of the last-mentioned edge being appreciably rounded, while the outline of the opposite

edge between points near its ends is relatively straight.

In the drawings, *a* is the handle, which may be of usual contour, and *b* is the blade, which from a substantially longitudinally central line *c* is inclined comparatively abruptly on both sides to the edge *d*, and from the same 30 line is inclined on both sides appreciably more gradually to the edge *e*. The outline of the edge *d* is appreciably rounded, while the edge *e* from a point near its ends is relatively straight in outline.

What I claim is—

The design for a combined cleaver and knife, as herein shown and described.

In testimony whereof I have signed my name to this specification, in the presence of 40 two subscribing witnesses, this 7th day of October, A. D. 1896.

EDWARD D. WOODS.
